UNITED STATES PATENT OFFICE

PHILIP KOCHER, OF BALTIMORE, MARYLAND

COMB

Application filed February 26, 1932. Serial No. 595,281.

This invention relates to combs, and especially to a comb for combing and exercising the hair on a person's head.

One object of my invention is to provide an improved hair-comb that exerts first a wedging action and next a firm and uniform traction effect upon the hair shafts without tearing or jamming the hair and thus to act 5 gymnastically upon the several related facets of the hair and scalp, to stimulate blood circulation in the scalp, to render the tight thin and dry condition of the scalp loose and flexible, to extract the discharged dead hair from the follicle, without injury to those 10 hairs which are in active and healthy condition, to loosen and remove dandruff, dust and dirt, while obviating the tearing and breaking of the hair by jamming and tightly holding the hair, and to prevent the clogging of 15 dirt and grease between the teeth at their base.

The details of this invention are illustrated in the accompanying drawing in which:

Figure 1 is an enlarged side elevation of a 20 comb which is constructed in accordance with this invention.

Figure 2 is a sectional view along the line 2—2 of Figure 1.

Referring to this drawing in detail, in 25 which similar reference characters refer to similar parts in both views, the details of the invention are now described as follows:

The back or base 5 is united with one or 30 more sets of teeth 6, and all of such teeth may be of the same size and shape, or of different 35 sizes and dimensions, while having the same general shape, and adapted to perform the same functions. In the present illustration, I have shown two sets of teeth 6, the teeth of 40 one set being larger or coarser than those of the other set. The purpose of making the comb with two sets of teeth, as shown, is to make it applicable for hair which is relatively fine and thin and for hair that is relatively coarse and thick, as will become more

apparent as the construction of the comb is better understood. However, instead of making a comb with teeth of different sizes, it is within the scope of this invention to make each comb with teeth of a uniform size, 50 and to make different combs with different size teeth.

The novel and important feature of this comb lies in the shape of the teeth, in their spaced relation to one another, and in the 55 junctions of the teeth with the head or base 5. With reference to the shape of the teeth, it will be observed that they have parallel complementary intermediate surfaces 9 which are very closely spaced from one another and extend considerable distances inward and outward from the middle of the respective teeth; the outer free end portion 6 of each tooth being wedge-shaped or outwardly 60 converging, so their complementary surfaces 10 converge to the closely spaced surfaces 9 and merge therewith. The inner end portion of each tooth is wedge-shaped, so that the complementary surfaces 8 of these inner 65 end portions diverge inwardly or toward the base 5 where they merge with cross-curved or convex-concave surfaces 7—7a of the head or base 5. Each of these convex-concave surfaces is upwardly or outwardly concaved, as shown in Fig. 1, and has two opposite edges merging with two adjacent complementary inwardly diverging inner end surfaces 8, while its other two opposite edges are convexed 70 and merge with the lateral sides of the head 5, as shown at 7a in Fig. 2. This formation of the head, at the bases of the teeth, and therebetween, appears to be quite novel, so no single word is found to describe it, and therefore, the coined compound word "convex-concave" is used and seems quite appropriate. Such convex-concave surfaces entirely eliminate sharp edges or corners at the bases of the teeth, and thereby eliminate the detrimental effects that such sharp edges 75 or corners have on the hair shafts. 80

Between the outer ends 11 of the teeth, and between the complementary surfaces 10, outwardly flared spaces 12 are provided to receive relatively large groups of hair shafts 5 as the ends 11 are forced or pass between such groups; and the complementary inwardly converging surfaces 10 wedge and compress the groups of hair shafts more and more until they enter the narrow space between the 10 complementary intermediate parallel surfaces 9 whereby a sliding and limited pulling of the hair shafts is effected while the latter pass from the outer end to the inner end of each pair of complementary intermediate parallel surfaces and until the hair shafts enter the widening spaces between the pairs of complementary inwardly diverging surfaces 8, whereupon the hair shafts are released from the grip or holding effect of the teeth and 15 permitted to pass out, easily, freely and unbroken, from between the bases of the teeth.

It is evident that a comb of this kind can be manufactured from various kinds of materials, and either stamped and pressed into 20 shape, moulded or formed by cutting tools, or by a combination of such devices.

To facilitate a full and clear understanding of the advantages of my improved comb, over the usual form of combs, I mention the 25 following distinctions:

The perpendicular outside face structure 30 of the teeth from point to base of combs currently in use are practically uniform; and their dimensions of interspaces from point to base between the teeth are virtually equidistant. I find that combs with teeth and interspaces so constructed fail to act upon the hair effectively. The hair received at the point passes through this equidistant interspace, and is delivered freely at the base 35 without any traction effect on the hair shaft. The practical use of such a comb is confined to disentangling and dressing of the hair.

A firm and uniform traction effect, wanting in the ordinary comb, is obtained in my comb by teeth which are wedge shaped on both ends, point and junction. A certain quantity of hair, received in the relatively wide openings at the points of my comb 40 teeth, is tractionally acted upon firmly and uniformly by being passed through the gradually reduced interspaces, which, after developing the greatest tension in the narrow intermediate part of the interspace, releases 45 its grip on the hair shafts as they pass into the interspaces between the teeth at their junction with the head 5.

These novel teeth and interspaces augment the utility of my comb variously. Besides 60 serving as a utensil to arrange and disentangle the hair as does the ordinary comb; my comb, by its firm and uniform traction effect upon the hair shafts, acts at once to exercise the hair roots, to stimulate circulation, to loosen the tight, thin, and dry condi-

tion of the scalp, and to free the follicle from the obstruction of the discharged dead hair by extracting it.

I also observe that the ordinary comb, particularly those with closely set teeth collect dirt and grease freely, and require frequent cleaning; and that this equidistance, from point to base between the teeth, permits the hair to be jammed and often injured by a sharp and solid base. In my comb the 70 clogging of matter between the teeth at their base is obviated, by an enlarged interspace between the teeth, at their junction.

Although I have described this embodiment of my invention quite specifically, I do not intend to limit my patent protection to these exact details of construction, for the invention is susceptible of numerous changes within the scope of the inventive ideas as implied and claimed.

What I claim as my invention is:

1. A comb comprising a series of teeth having adjacent complementary parallel intermediate surfaces, outwardly diverging complementary outer end surfaces merging with said parallel intermediate surfaces, and inwardly diverging complementary inner end surfaces merging with said intermediate surfaces and with curved surfaces which extend from the base of each tooth to its next adjacent tooth.

2. A comb consisting of a head and a single row of teeth integrally united with one another, said teeth having complementary intermediate surfaces which are so closely spaced from one another as to wedgily clamp and frictionally engage with groups of hair shafts and thereby pull the hairs that slide therebetween and thus remove dead hairs and dandruff while stimulating the scalp by the pulling of the live hairs without removing the latter from the scalp, said teeth having complementary outer end surfaces which are widely spaced from one another at their extreme outer ends and converge thence toward and merge with the complementary intermediate closely spaced surfaces for leading and gradually compressing the groups of hair shafts into the space between the said closely spaced surfaces, said teeth having complementary inner end surfaces which merge with said complementary narrowly spaced surfaces and diverge therefrom towards said head and thereby provide clearance spaces wherein the clamping frictional engagement of the hair shafts is relieved to permit the hair shafts to pass freely and unbroken from between the inner ends of the teeth.

3. The structure defined by claim 2, said complementary intermediate closely spaced surfaces extending considerable distances inward and outward from the middle parts of the respective teeth and being parallel throughout their length, for prolonging the

said frictional engagement of the hair shafts.

4. The structure defined by claim 2, said head having surfaces which are concaved from one of said teeth to another of said 5 teeth and merge with adjacent inner end surfaces, and these concaved surfaces having convexed edges that merge with the opposite sides of the said head, thereby eliminating sharp edges and corners which would 10 tend to mar the hair shafts as the latter pass from between the bases of the teeth.

In testimony whereof I affix my signature.

PHILIP KOCHER.
